(Cl. D33—14)

To all whom it may concern:

Be it known that I, Robert A. Guichard, a citizen of the United States and a resident of Chicago, in the county of Cook and State of Illinois, have invented a new, original, and ornamental Design for an Adjustable Stand or Similar Article, of which the following is a specification, reference being had to the accompanying drawing forming a part thereof, and in which:

Fig. 1 is a perspective view of an adjustable stand or similar article, showing my new design;

Fig. 2 is a top plan view thereof; and

Fig. 3 is an end view thereof.

I claim:

The ornamental design for an adjustable stand or similar article, as shown.
